UNITED STATES PATENT OFFICE

SAMUEL L. McVEY, OF SAN JOSE, CALIFORNIA

SLEEVE STEAMER

Application filed April 15, 1930, Serial No. 444,432. Renewed May 3, 1932.

The invention is for a sleeve steamer, and has special reference to pressing and steaming equipment as used in pressing and cleaning establishments.

5 The main object of the invention is to provide a steamer especially adapted to the steaming of sleeves of garments, and which is specially formed to suit the sleeve and shoulder and on which the sleeve is readily applied and removed.

10 Another object of the invention is to provide a device as outlined which may be maintained in a constantly heated condition, the steaming being applied as required, and the steam thereby being supplied as a dry steam, preventing the throwing of water.

15 A further object of the invention is to provide a device as above outlined which is simple in construction and operation, which is readily connected to any steam supply, which requires only one valve for operation, and is provided with but one steam connection.

20 Other objects of the invention will become apparent as the description is set forth when read in conjunction with the accompanying drawing, in which:

Fig. 1 is a side elevation of the steamer;

25 Fig. 2 is a sectional longitudinal elevation through the steamer head;

30 Fig. 3 is a sectional elevation taken on line 3—3 of Fig. 2.

The invention consists primarily of a two compartment head, one of the compartments being provided with a threaded aperture to receive a steam connection and being closed against the escape of steam except by means of a valve into the second chamber which is provided with a multiplicity of small apertures through which the admitted steam escapes when the valve is actuated, the head consisting in external form of a long tapered arm of circular or rounded cross-section, increasing in diameter to and terminating in a rounded shoulder, continuing into a depending leg or standard. The closed steam compartment is disposed in the lower half of the arm and inner side of the stand, a well dividing the arm longitudinally in a horizontal plane. The valve extends below the

stand and communicates with the closed and apertured compartments and is operated by a foot treadle.

Similar character references are used to designate similar parts throughout the several views.

The head, Fig. 2, consists of the tapered arm 3, standard 4, and foot 5. A transverse wall 6 divides the arm 3 and standard 4 into two compartments 7 and 8, the compartment 7 being entirely closed except at 9, providing an outside steam connection, and at 10 and 11 arranged for reception of a valve for permitting steam to enter chamber 8 from chamber 7 through the valve at 11, the aperture 10 being sealed by the valve against escape of steam. A multiplicity of small apertures 12 permit escape of the steam into the fabric or sleeve of the garment. The standard end of the arm 3 is rounded as at 13 over which the shoulder portion of the sleeve fits, and the foot 5 is provided with apertures to receive screws or bolts 14 for fastening to a table 15 which is fastened to the stand 16.

The valve may be of any standard suitable make, and is indicated as a plunger type of valve consisting of a plunger 17 suitably fitting a cylinder 18 which is in screw threaded engagement in the aperture 11, and is provided with a series of small apertures 19, whereby, when the plunger 17 is partially withdrawn, certain of the apertures 19 are uncovered, permitting steam to escape from chamber 7 through apertures 19 and cylinder 18 into the chamber 8, thence out through apertures 12. A foot pedal 20 normally retained in raised position by a spring not shown is connected by the rod 21 to valve plunger 17 keeping the valve normally closed. A packing gland 22 seals the recess 10 and cylinder 18 against escape of steam thereabout.

The operation of the device is as follows: A supply of steam is retained under pressure from a boiler or other source in compartment 7 by means of the pipe 23. The sleeve of a garment is drawn over the arm 3 until the shoulder passes about the rounded end 13, the collar hanging down back of the stand 4. The entire head is heated by the steam

in compartment 7, the water of condensation flowing out through pipe 23. Foot treadle 20 is then depressed, pulling the plunger 17 downward by means of the rod 21, thereby opening one or more of the ports 19 and permitting steam to escape from chamber 7 to chamber 8 thence through apertures 12 and through the cloth or fabric of the sleeve, release of treadle 20 immediately shutting off the escape of steam into the chamber 8.

Having described an operative method of constructing and operating the device, it will be noted that such variations in design, construction and arrangement of parts which are consistent with the scope of the appended claims may be resorted to without departing from the spirit or scope of the invention or sacrificing any of the advantages thereof.

I am aware that prior to my application, steamers and presses have been made, therefore I do not claim such a device broadly, but I do claim:

1. A sleeve steamer comprising a tapered hollow arm provided with a wall therein whereby said arm is longitudinally divided into two chambers of semi-circular cross-section, the outside surface of said arm being of substantially circular cross-section, a standard and a foot integral with said arm and continuing at substantially right angles to said arm, said dividing wall continuing downward in said standard thence closing off one chamber from the other, a steam connection communicating with the inner and lower of said chambers, a valve communicating with the inner and lower chamber and with the other chamber, and a multiplicity of ports in the outer wall of said other chamber.

2. A sleeve steamer, comprising a tapered hollow arm of cylindrical cross-section, the larger end thereof continuing at right angles downwardly terminating in a standard and a base, a dividing wall continuing lengthwise through said arm and said standard adjacent to said base, forming thereby a pair of chambers, one of said chambers constituting a heating chamber and having a steam inlet therein, the other of said chambers constituting a steaming chamber and having communication with said heating chamber by means of a foot treadle operated valve, a multiplicity of ports distributed about the outer wall of said steaming chamber and communicating therewith, the coincident portion of said arm and standard being formed with well rounded surfaces to conform to the shoulder of a garment.

In testimony whereof I have affixed by signature.

SAMUEL L. McVEY.
